UNITED STATES PATENT OFFICE

HERMAN O. BECKLIN, OF SEATTLE, WASHINGTON

WRENCH

Application filed July 16, 1928. Serial No. 293,006.

This invention relates to wrenches and more especially to improvements in the wrench which is illustrated and described in U. S. Patent No. 1,334,156, dated March 16, 5 1920.

The object of the present invention, generally stated, is to perfect the construction and arrangement of the wrench parts to render the same more simple, strong and durable, and more convenient and efficient in operation.

An important object of the invention is to provide a wrench of the above character which is formed of relatively few and simple parts that may be readily removed for cleaning or repair.

Other objects and advantages of the invention will appear in the following description.

The invention consists in the novel construction, adaptation and combination of parts hereinafter described and claimed.

In the accompanying drawing,—

Figure 1 is a side elevation of a wrench embodying my improvements; Fig. 2 is a transverse sectional view on line 2—2 of Fig. 1; Fig. 3 is a perspective view of the yoke; and Fig. 4 is a similar view of the lock member for the movable jaw.

In said drawing, the reference numeral 5 20 represents a bar member having at one end a handle portion 6, and at its other end a jaw 7, hereinafter termed the fixed jaw. The top surface of the bar is formed with teeth 8 extending entirely across the bar. Formed 25 with or rigidly secured to the jaw end of said bar is a frame 9 provided above the bar with an opening 10 which serves as a guideway for the shank 11 of the movable jaw 12.

At its end opposite the jaw 12, the shank 40 11 is pivotally connected by means of a pin 13 with an end of a yoke 14 which is mounted upon the bar member 5 for movement with the movable jaw 12 longitudinally of the bar.

The pivotal connection afforded by the pin 45 13 permits movement of the jaw 12 independently of the yoke in the plane of the wrench, and limited by the vertical opening of the guideway 10.

15 represents a spring provided within the frame 9 to act against the shank 11 of the

movable jaw for yieldably holding the latter to the work. The construction of the yoke 14 which constitutes an important part of the present invention comprises a hollow block with an opening 16 (Fig. 3) extending longitudinally therethrough and of a transverse section to fit the bar 5 for relative sliding movement.

Intermediate its length the yoke is provided with a recess 17 extending from the plane of its top surface 18 of the yoke to below the top of the opening 16 for the bar 5, the surfaces 19¹ and 20¹ of the yoke portions 19 and 20 at the front and rear, respectively, of said recess are arranged parallel and at right angles to the said bar.

The portion 19 is, moreover, bifurcated to provide at the front lugs 21 with a space 22 therebetween to accommodate the shank 11 and which latter is connected to the yoke by 70 engaging the referred to pin 13 in apertures, such as 23, provided in the lugs.

Located between the yoke portions 19 and 20 is a block 28, hereinafter termed the dog, having plane front and rear end surfaces adapted to fit against the yoke surfaces 19¹ and 20¹ and provided in its underside with a series of teeth 29 which are adapted to interengage with the teeth 8 of the bar member.

The dog is connected to the yoke by means of a bolt 24 disposed longitudinally of the wrench and extending through holes 25 and 26 provided in the dog and the yoke portions 19 and 20 to the front and rear respectively of the yoke recess 17.

The bolt 24 is arranged at one side of the midwidth of the dog and yoke, and is provided with a head 24¹ within the yoke recess 22 and is secured in place by means of a nut 27 taking screw threads provided on the bolt and engaging against the rear end of the yoke.

Said dog is provided with a fin element 28¹ extending upwardly from the recess 17 and thence rearwardly over the top of the yoke element 20, whereby the operator pushing laterally with his fingers or thumb against the fin will impart rotary movement of the dog to cause the teeth thereof to be brought

into or out of engaging relation with the teeth of the bar member.

The position of the dog in its engaged or locking position is illustrated by full lines in Figs. 1 and 2, and in its disengaged position by dotted lines 28^a in Fig. 2.

31 represents a spring pressed ball carried by said dog and is adapted to engage in cavities 30 or 30¹ provided in the yoke for releasably connecting the dog thereto in its coupled or disengaged positions with respect to the bar member of the wrench.

32 represents a split pin adapted for detachably securing the pin 13 to the yoke and permitting the pin 13 to be removed to release the movable jaw, whereupon the bolt 24 can be withdrawn from the yoke for the removal of the dog.

In operation the wrench is adjusted after turning the dog 28 into its dotted line position 28^a (Fig. 2) position to disengage the dog from the rack teeth 8 of the wrench-bar 5.

The disengagement of the dog releases the yoke which may then be manually shifted lengthwise of the bar to carry the movable jaw into engageable relation with the work.

With the wrench thus adjusted the dog is returned from its dotted line 28^a position into its full line position in Fig. 2 resulting in the reengagement of the dog with the bar 5 for locking the yoke thereto and the movable jaw 12 in position to cooperate with the fixed jaw 7.

It is to be noted that in the present invention, that the yoke 14 is of a single piece mounted to slide upon the wrench bar, and that the yoke is provided with a recess open at the top of the yoke whereby the dog is adapted to be readily removed or replaced and that it is held in place between thrust bearings by means of a removable bolt.

What I claim, is,—

1. In a wrench, the combination with the bar member having teeth on its upper surface and a fixed jaw, of a yoke slidable upon the bar, said yoke having a recess opening upwardly away from the bar between two post elements of the yoke, a movable jaw pivoted on the yoke, a locking dog located within said recess in contiguous bearing relation with the opposing faces of said posts, a bolt engaged in both of said posts and serving to support the dog for rotary movement, said dog having teeth adapted by turning the dog about the axis of said bolt to be brought into and from locking relation with the bar teeth, said dog having a thumb-piece integral therewith and extending upwardly from said recess and thence over one of said yoke posts, and spring actuated latch devices carried by said dog-thumb extension and engageable in said last named yoke post for releasably holding the dog in either its engaged or disengaged relation selectively with respect to the bar teeth.

2. In a wrench, the combination with the

bar member having teeth on its upper surface and a fixed jaw, of a yoke slidable upon the bar, said yoke having a recess opening upwardly away from the bar between two post elements disposed one in front of the other, and a second recess provided in the foremost of said posts, a bolt engaging in said posts and extending through the first named recess and into the second recess, a removable jaw pivoted on the yoke, a locking dog rotatably connected within the first named recess to said bolt, said removable jaw having a shank extending into the second named recess, and serving when attached to the yoke to prevent the removal of said bolt to release the dog for its removal from the yoke, said dog having teeth adapted by turning the dog to be moved into and from locking relation with the bar teeth, said dog having a thumb-piece integral therewith and extending over one of said yoke posts, and latch devices carried by said thumb-piece and engageable with said yoke post for releasably holding the dog in its engaged or disengaged relation with respect to the bar teeth for securing the yoke in an adjusted position to the bar.

Signed at Seattle, Washington, this 22 day of June 1928.

HERMAN O. BECKLIN.
